UNITED STATES PATENT OFFICE

111,518

DESIGN FOR A STAND FOR PERFUME BOTTLES

Lucien Lelong, Paris, France, assignor to Lucien
Lelong, Inc., Chicago, Ill., a corporation of Illinois

Application June 15, 1938, Serial No. 77,858

Term of patent 7 years

To all whom it may concern:

Be it known that I, Lucien Lelong, a citizen of the Republic of France and a resident of the city of Paris, in the country of France, have invented a new, original, and ornamental Design for a Stand for Perfume Bottles, of which the following is a specification, reference being had to the accompanying drawing, forming a part thereof.

On the drawing:

I claim:

The ornamental design for a stand for perfume bottles, as shown.

LUCIEN LELONG.
